UNITED STATES PATENT OFFICE.

BENCE D. GRIFFITH, OF MASON CITY, IOWA.

PARAFFIN-MACHINE.

1,172,790.

Specification of Letters Patent.

Patented Feb. 22, 1916.

Application filed February 27, 1915. Serial No. 11,076.

To all whom it may concern:

Be it known that I, BENCE D. GRIFFITH, a citizen of the United States, and residing at Mason City, in the county of Cerro Gordo and State of Iowa, have invented certain new and useful Improvements in Paraffin-Machines, of which the following is a specification.

This invention relates to machines for applying paraffin to the interior of pails or other vessels, and its primary object is to provide a device of this character by means of which the paraffin is melted or liquefied by the action of steam and also directed into and sprayed against the interior of the vessel being treated.

The construction of the improvement will be fully described hereinafter in connection with the accompanying drawing which constitutes a part of this specification, and its novel features will be set forth and defined in the appended claims.

In the drawing: Figure 1 is a front elevation of one form of the improved apparatus, the same being what may be termed a double construction, employing two independent paraffin reservoirs, and Fig. 2 is a central vertical sectional view illustrating a single paraffin reservoir or receptacle.

30 The reference numeral 1 designates a cylindrical or tubular member provided with a base 2 adapted to be secured by suitable means as screws 3 to a floor. To the upper end of the tubular member 1 is connected by means of a T-coupling 4, a cylindrical paraffin reservoir or receptacle 5 having an open lower end 6 and terminating at its upper end in a spray nozzle 7 suitably perforated as shown. The upper portion of the reservoir 5 immediately below the nozzle 7 is of conical form as shown at 8 and this conical portion is formed with a plurality of openings 9 for the purpose hereinafter explained.

45 Supported upon the reservoir 5 is a collar 10 provided at its upper end with an annular horizontal flange 11 which supports a dish-shaped holder 12 provided with an annular flaring flange 13. The bottom 14 of the holder 12 is provided with a central opening through which the conical upper end of the paraffin reservoir 5 projects and said holder is supported upon the flange 11 of the collar 10 as clearly shown in Fig. 2. The pail or

other vessel 15 is supported in inverted position as shown in Fig. 2 upon the holder 12.

Communicating with the nozzle 7 of the paraffin reservoir is a tube 16 open at its lower end and connected by a coupling 17 to an elbow 18 having connection with a steam inlet pipe 19 controlled by a valve 20.

The utility and operation of the apparatus constructed as above described will be readily understood. Paraffin is supplied to the space within the cylindrical member 4 and when steam is turned on, it liquefied the paraffin, which feeds upward through the lower open end of the reservoir 5, and is discharged or sprayed under the pressure of the steam through the nozzle 7, thereby distributing it against the interior of the vessel 15 to coat the latter. It will thus be noted that the steam not only melts or liquefied the paraffin but also ejects it from the reservoir 5 in the manner already explained. The openings 9 adjacent the upper end of the reservoir 5 afford means for escape for surplus liquid paraffin, directing it back as illustrated in Fig. 2, to the reservoir.

I preferably provide the paraffin holder 4 with a drain pipe 4' equipped with a valve 4" to draw off the contents of the member 4 when desired.

What I claim as new is:

1. In a paraffin machine, the combination with a base support, of a hollow receptacle or container for paraffin open at its lower end and terminating at its upper end in a discharge nozzle, of a tubular connection between the lower open end of said reservoir and base adapted to contain paraffin, a tubular member within said reservoir or container, and a steam supply pipe connected to the lower end of said tubular member.

2. In a paraffin machine, the combination with a supporting base, of a paraffin reservoir open at its lower end, a hollow coupling between the lower end of said reservoir and base, a spray nozzle at the upper end of said reservoir, a tubular member within said reservoir open at its lower end and communicating at its upper end with said nozzle, and a steam supply pipe connected with the lower end of said tubular member, said reservoir being formed with openings adjacent to its upper end for the return of surplus paraffin to the reservoir.

3. In a paraffin machine, the combination with a vertically-disposed hollow paraffin reservoir or container open at its lower end, a cylindrical member connected to the lower end of said reservoir and adapted to contain paraffin, a tubular member within said reservoir, a steam supply pipe connected to the lower end of said tubular member, a vessel holder mounted upon the upper portion of

said reservoir and having an annular flaring flange, and a flanged collar mounted upon the upper end of said reservoir.

In testimony whereof I affix my signature in presence of two witnesses.

BENCE D. GRIFFITH.
